UNITED STATES PATENT OFFICE

139,302

DESIGN FOR A BUTTON OR SIMILAR ARTICLE

William Drell, New York, N. Y.

Application September 12, 1944, Serial No. 115,273

Term of patent 3½ years

(Cl. D17—2)

To all whom it may concern:

Be it known that I, William Drell, a citizen of the United States of America, residing in the city of New York, county of New York, and State of New York, have invented a new, original, and ornamental Design for a Button or Similar Article, of which the following is a specification, reference being had to the accompanying drawing, forming part thereof.

Fig. 1 is a plan view of a button or similar article, showing my new design.

Fig. 2 is an edge view thereof.

I claim:

The ornamental design for a button or similar article, substantially as shown.

WILLIAM DRELL.
